RAILWAY JOURNAL BOX LUBRICATOR
STRUCTUREJames J. Hennessy, Chambersburg, Pa., assignor
to Hennessy Lubricator Company, Inc., Cham-
bersburg, Pa., a corporation of Delaware

Application February 4, 1950, Serial No. 142,435

13 Claims. (Cl. 308—84)

1

The invention relates to railway axle journal box lubricators of the type in which a pump in the journal box is actuated by the play of the journal crosswise of the box to pump lubricant from the bottom of the box to the surface of the journal.

One of the problems in providing a lubricator of this type is the matter of installing and removing the pump, when the box and journal are assembled, without jacking up the box, removing the wedge or bearing or bolt and then dropping the box onto the journal so as to provide more room to insert the lubricator through the box opening into the space beneath the journal. The main object of the present invention is to facilitate the insertion of a pump into the space between the journal and the bottom of the box without the necessity of jacking up and dropping the box as described and without the necessity of unduly restricting the size of the pump and associated parts or the necessity of making the lubricator in a plurality of separate parts which must be assembled after insertion into the box.

This object is attained by arranging the box and the lubricator pump to position the pump forwardly of the box beyond the end of the journal and preferably this arrangement includes the provision of an opening in the lower outer portion of the usual box front wall with an adjacent housing or recess for receiving the pump extending forwardly of the box beyond the usual contour, there being structure for closing the opening in the box front wall against the loss of oil or admission of dirt, moisture, etc.

In the accompanying drawings, which illustrate the invention,

Figure 1 is a vertical longitudinal section through an axle journal box equipped with the invention, the associated axle journal being shown in elevation.

Figures 2 and 5 are detail vertical sections taken on the corresponding section lines of Figure 1.

Figure 3 is a detail top view of the pump and pump operating mechanism and is taken upon the line 3—3 of Figure 1.

Figure 4 is a vertical transverse section taken on the line 4—4 of Figure 3 and drawn to enlarged scale.

Figure 6 is a vertical section corresponding to the left hand portion of Figure 1 but illustrating another form of the invention.

Figure 7 is a vertical transverse section taken on the line 7—7 of Figure 6.

Figure 8 is a horizontal section taken on the line 8—8 of Figure 6.

2

The box 1 shown in Figures 1—5 resembles the usual box having a bottom wall 2, side walls 3 and a top wall 4 which seats a wedge 5 and a bearing 6, all mounted upon the journal 7 of the general type. The box will have the usual opening 8 in its front wall extending downwardly to accommodate the insertion and removal of the wedge and bearing and this opening will be provided with the usual lid (not shown).

10 Below opening 8 and extending forward and upwardly from the box bottom wall 2 is a front wall provided with an opening 9 having bottom, top and side edges and adapted to receive a housing having a bottom 10, sides 11, a top 12 and a front 13 forming a closure for the opening 9. Preferably the housing bottom 10 extends inwardly of the box along the bottom wall 2. The housing may be welded to the box as indicated at W forming a joint around the housing.

15 20 A distributor 14 has a length corresponding generally to the bearing surface of the journal and has a width corresponding generally to the diameter of the journal. The distributor 14 and the springs 8 which support it from the bottom of the journal box may be readily inserted through box opening 9 before the housing is applied or may be inserted through the usual opening in the upper portion of the box front wall into position beneath the journal as there is no pump beneath the journal which the lubricator must clear. The distributor includes an arcuate pan-like member 15 filled with felt or woven or sewn strands of wool or other similar fibrous material 16.

25 30 35 A lubricant pump structure is positioned in the housing and includes duplicate pairs of upright chambers 17 and 18, at least one chamber of each pair having flexible sides. Each pair of chambers 17 and 18 is mounted upon the left hand end of a substantially horizontal lever 19 and these levers are pivoted to upstanding ribs 30 on a bracket 31 which is slidable inwardly of the box from the position shown in which a lip 32 at its inner end engages the inner edge of housing bottom 10, the outer end of the bracket being beneath a holding piece 33 welded to the housing bottom at X (Figure 5). Levers 19 are actuated by a lever 21 pivoted at 22 to the bracket ribs 30 and have a journal engaging element 23. Levers 19 and 21 have inter-engaging arms 24 and the parts are so arranged that as the journal moves axially crosswise of the box, its left-hand movement will elevate the left hand end of lever 19 and chambers 17 and right-hand movement of the journal will release chambers 17 and permit springs 25 and 26 to expand chambers 17 to

position shown in Figure 1 where their upper ends are seated against a ledge 34 on the housing front 13. Return check valves 27 and 28 provide for the intake and discharge of lubricant from chambers 17 to chambers 18 from whence it is lead through conduits 29 to the distributor at points intermediate the ends of the journal.

Figures 6, 7 and 8 illustrate another form of the invention in which the journal box 40 and journal 41 correspond with those previously described. The box front wall 44 has an opening 45 similar to opening 9. The distributor 46 may be the same as that shown in Figure 1 and the housing 43 in the front wall opening 45 is substantially the same as that previously described. The pump structure is of the cylinder and piston type and includes a pair of levers 47 pivoted at 48 on ribs 49 welded to the housing bottom and extending upwardly from their pivots to terminate in elements 50 disposed to be engaged by the end of the journal as it plays back and forth crosswise of the box. Associated with each lever 47 is a spring thrust piston 51 received in a cylinder 52 forming a part of or mounted upon housing 43. Upstanding chambers 54 at the inner ends of cylinders 52 have return check valves 55 and conduits 56 leading to distributor 46.

In both forms of the invention, the pump and distributor are structures which may be made rigid and of substantial size and readily applied to the journal without the inconvenience of having them formed of hinged parts to facilitate insertion into the space directly beneath the lower center portion of the journal. Hence, it is comparatively easy to provide pumps and distributors of desired size and without the fitting of separately formed parts as has characterized some pumps of this general type used heretofore.

The details of the structure may be varied substantially without departing from the spirit of the invention and the exclusive use of those modifications coming within the scope of the claims is contemplated.

What is claimed is:

1. In a railway axle journal lubricator, a box having a top wall for seating the usual journal wedge and bearing, a bottom wall, and a front wall extending between said top and bottom walls, there being an opening in said front wall adjacent said bottom wall, and a lubricant pump positioned in said latter-mentioned opening above the bottom of the box and provided with a pump actuating member extending inwardly of the box and longitudinally of the box, and an associated operating element disposed to engage the end of a journal in the box.

2. In a railway axle journal lubricator, a box having a top wall for seating the usual journal wedge and bearing, a bottom wall, and a front wall extending between said top and bottom walls, there being an opening in said front wall adjacent said bottom wall and above the level thereof, and a housing projecting outwardly from the end of the box above the level of said bottom wall and having a top, a bottom and sides fitting the top, bottom and sides of said opening, said housing forming a front closure for said opening, and a lubricant pump structure mounted in said housing and provided with an actuating member extending into the box to contact a journal therein.

3. In combination, a railway axle journal, a bearing, a wedge and a box mounted thereon having a bottom wall and a front wall, there being an opening in the lower portion of said front

wall adjacent said bottom wall, a lubricant distributor insertible horizontally through said opening into position beneath the journal, a pump, a pump operating mechanism positioned, at least in part, in said opening, and a lubricant conduit leading from the pump inwardly along the side of said journal to a point on said distributor intermediate the ends of the journal.

4. A structure as described in claim 3 in which duplicate conduits lead from said pump structure along opposite sides of the journal to points on said distributor intermediate the ends of the journal.

5. In combination, a railway axle journal box including top, bottom and front walls, there being an opening in the front wall extending upwardly from the box bottom wall, a housing secured in and forming a closure for said opening, and a pump mounted in said housing above the level of said bottom wall and comprising an upright collapsible chamber with flexible side walls having a return check inlet valve at its lower end and a return check outlet valve spaced above said inlet valve and journal contacting means for collapsing the pump chamber, and conduits leading from said outlet valve inwardly and upwardly of the box.

6. In combination, a railway axle journal box including top, bottom and front walls, there being an opening in the front wall extending upwardly from the box bottom wall, a housing secured in and forming a closure for said opening, a pump structure mounted in said housing outwardly of the box front wall, and a pump actuating mechanism mounted on a portion of said housing inwardly of said front wall and including a pivoted lever disposed to be engaged by a journal upon which the box is mounted.

7. In combination, a railway axle journal box including top, bottom and front walls, there being an opening in the front wall extending upwardly from the box bottom wall, a housing secured in and forming a closure for said opening, a lubricant distributor comprising an upwardly facing concave lubricant conducting device of less width than the width of said opening and insertible through said opening and supported from said bottom wall, and a pump mounted in said housing and comprising an upright collapsible chamber having a return check inlet valve at its lower end and a return check outlet valve spaced above said inlet valve, and conduits leading from said outlet inwardly and upwardly of the box to said distributor.

8. In combination, a railway axle journal box including top, bottom and front walls, there being an opening in the front wall extending upwardly from the box bottom wall, a housing secured in and forming a closure for said opening, a lubricant distributor comprising an upwardly facing concave lubricant conducting device of less width than the width of said opening and insertible through said opening and supported from said bottom wall, said distributor comprising a substantially rigid pan-like member having a length and width corresponding to the length and diameter of the journal to which the box is to be applied and having a spring supporting the distributor from the bottom of the box.

9. In combination, a railway axle journal box including top, bottom and front walls, there being an opening in the front wall extending upwardly from the box bottom wall, a housing secured in and forming a closure for said open-

ing, a lever pivoted on said housing with an arm extending upwardly from its pivot and an arm extending outwardly from its pivot, a collapsible pump mounted on the outer end of said latter-mentioned arm with its upper end confined by said housing, and a journal contacting element mounted on the upper end of said first-mentioned arm.

10. In combination, a railway axle journal, a box mounted thereon and including top, bottom and front walls, there being an opening in the front wall extending upwardly from the box bottom wall, a housing positioned in and forming a closure for said opening, a pair of levers arranged side by side transversely of the box each being pivoted on the housing and extending upwardly from its pivot and terminating in an element disposed to engage the end of a journal upon which the box is mounted, a lubricant pump mounted in said housing and including cylinder and piston structure associated with said levers, and passageways provided with return check valve structure leading from said cylinder and piston structure inwardly of the box and discharging to opposite sides of said journal.

11. In combination, a railway axle journal, a bearing, a wedge, and a box mounted thereon having a bottom wall and a front wall, a pad-like lubricant distributor member applied to the lower face of said journal, a spring supporting said member from the bottom of the box beneath the journal, a lubricant pump mounted in said box outwardly of the forward end of said journal at least partly above the level of the bottom of the journal, a pump operating mechanism positioned between the outer end of said distributor and the front wall of the box, and a lubricant conduit leading from the pump to said distributor.

12. In combination, a railway axle journal, a bearing, a wedge, and a box mounted thereon having a bottom wall and a front wall, a lubricant pump mounted in the box forwardly of the box beyond the end of said journal, a pump operating mechanism positioned between the outer end of said journal and the front wall of the box and engageable by the end of the journal, and means for conducting lubricant from said pump to said journal at points on the latter intermediate its ends.

13. In combination, a railway axle journal box having side walls, a top wall for seating the usual journal wedge and bearing, a bottom wall, and a front wall curving forwardly and upwardly from said bottom wall beyond the outer end of said top wall and forming, with the front edge of the latter and front edges of said side walls, the usual journal box opening at the level of a journal upon which the box, bearing, and wedge are mounted, there being an opening in said front wall between said bottom wall and said first-mentioned opening, a lubricant pump positioned in said second-mentioned opening, and means for conducting lubricant from said pump inwardly of the box to points spaced longitudinally of the box from said pump.

JAMES J. HENNESSY.
